UNITED STATES PATENT OFFICE

FRANK BENEDICT, OF RUTHERFORD, NEW JERSEY, ASSIGNOR TO GENERAL RAILWAY SIGNAL COMPANY, OF ROCHESTER, NEW YORK

POWER INTERLOCKING SYSTEM FOR RAILROADS

Application filed July 9, 1929. Serial No. 377,034.

This invention relates to power interlocking systems for railroads, and more particularly to means for safeguarding the operation of power operated switches, especially when it is necessary to operate them by hand, or under emergency conditions.

When it becomes necessary to operate a switch machine by hand, it is desirable that suitable provision be made to insure care and due responsibility in placing said switch machine back under normal power control. In one type of switch machine, to which the present invention is the specific form shown and described, is particularly applicable, before the hand crank for operating the machine manually can be used, power must be cut off from the switch machine, special contacts being provided for this purpose. It sometimes happens that these contacts are closed accidentally or carelessly after the hand cranking has been completed, at a time and under such conditions that an improper power operation of the switch may occur; and one object of the present invention is to provide means for safeguarding the restoration of the switch machine to normal power operation.

In the practical operation of power interlocking systems, it sometimes becomes expedient or necessary to operate a switch under special or emergency conditions, an emergency release device being commonly used for this purpose. Another object of this invention is to provide an improved type of emergency release device, which must be specially manipulated in order to operate a switch, so as to avoid careless or accidental misuse.

The characteristic features of the invention, and its advantages, will be in part apparent and in part pointed out as the description progresses.

The accompanying drawing shows in a diagrammatic and conventional manner one specific embodiment of the invention.

While the invention will take various forms, depending upon the type of interlocking system and conditions encountered in practice, an explanation of the invention, as applied to an electric interlocking system of the well known dynamic indication type, will make clear the features and functions of the

invention. Referring to the accompanying drawing, there is shown diagrammatically the usual control lever LV, electric lever lock L, with its latch contacts 5, an indication selector IS, indication magnet I, safety magnet S, and cross-protection relay CP. These parts and devices are of the usual construction, and operate in a way familiar to those skilled in the art, characteristic of this particular dynamic indication type of system, as more fully explained, for example, in the patent to Howe, No. 1,550,611, August 18, 1925. For the purposes of this invention, the electric lock L is preferably of the force-drop type, effective in the normal and reverse indication positions of the lever, as disclosed, for example, in the patent to Carter et al., No. 1,566,901, December 22, 1925.

Associated with the lever LV, and located in the tower, is a power control relay LR, which controls the supply of operating current to the contacts of the lever from the battery B, or other suitable source of current, over wire 6, through the front contacts 7 of the relay LR, arranged in multiple, wire 8 and fuse 9 to the safety magnet S. This relay LR is of any suitable construction capable of breaking switch machine operating current and is operable either on direct current or alternating current, depending upon the source of energy used; and when this relay LR is de-energized, power is cut off from the contacts controlled by the lever LV, and the switch machine controlled thereby can not be operated.

Also associated with the lever LV, and preferably located in the tower, is a relay P, conveniently called a protective relay, and a reset button RS. This protective relay P is of any suitable construction, and is provided with two front contacts 10 and 11. The reset button RS, shown diagrammatically, comprises a manually operable contact member 12, movable from a normal position as shown, out of engagement with cooperating contacts, indicated conventionally as arrows, into engagement with another pair of cooperating contacts.

In the tower is also an emergency release device ER, preferably of the screw release

type. In the simplified construction illustrated, this emergency release device ER comprises a rod or spindle 14, provided with a hand crank 15. One end of this spindle 14 is threaded into a support 16, and slides freely in another support 17. Suitable insulated contact discs or members 18, 19 and 20 are fixed to the spindle 14 and engage co-operating contacts indicated by arrows in the different longitudinal positions of this spindle. By turning the crank 15 the operator may move the spindle 14 back and forth to close and open circuits through these contact members 18, 19 and 20. This emergency release device ER has three different positions, one a normal position as shown, indicated by the dotted line 0, another position toward the left from the normal position, indicated by the dotted line 1, in which 5 the contact member 18 only completes a circuit through its co-operating contacts; and a third position, indicated by the dotted line 2, in which the contact member 18 only completes a circuit through another co-operating 10 pair of contacts.

The control lever LV serves to control the application of operating current over normal and reverse operating wires N and R and a common wire C, to a suitably electrically operated switch machine SM, connected to the points of the switch SW. This switch machine SM, shown conventionally, is preferably of the construction shown and described in the patent to Howe, No. 1,466,903, September 4, 1923. Associated with the switch SW is the usual signal 21, governing traffic over this switch, and the usual detector track circuit, comprising a track battery 22, or other source of current, and a track relay T, having a front contact 23.

The switch machine SM, as shown and described more in detail in said Howe Patent, No. 1,466,903, includes means for permitting its hand operation. This means includes a socket (indicated at 24 in the drawing) adapted to receive the end of a hand crank (not shown), so that by turning the crank, the gearing of the switch machine 15 may be operated by hand to unlock and operate the switch. This socket 24 for the hand crank is normally obstructed or partly covered by a guard plate 25, pivoted at 26, so arranged that the hand crank can not be inserted, until this guard plate is pushed aside to align an opening 25^a therein with the socket 24. The guard plate 25 is connected to a rod 27, carrying an insulated contact member 28 which normally completes a circuit through a pair of co-operating contact springs 29. When the guard plate 25 is shifted to permit hand cranking of the switch machine, the circuit through the contact 30 28 and the contact springs 29 is broken.

The parts are shown in the drawing in the

normal condition. The various circuits involved are shown for simplicity as terminating at the symbols (+) and (-), indicating the opposite terminals of a battery, or other suitable source of direct or alternating current. 70

The protective relay P is normally energized by a stick circuit which may be traced from (+) through the contact fingers 29 and contact 28 of the guard plate 25, wire 30, 75 front contact 10 of relay P, wires 31 and 32, relay P to (-).

The power control relay LR is normally energized by a circuit which may be traced from (+) through the front contact 23 of 80 the track relay T, wire 33, front contact 11 of relay P, wire 34, reset contact 12 and its normally closed contacts 35, wire 36, relay LR to (-).

The electric lever lock, upon actuation of 85 the latch contacts 5, may be energized by a circuit from (+) through the front contacts 23 of the track relay T, wires 33, 37 and 38, contact 19 of the emergency release ER, wires 39 and 40, latch contacts 5, wire 41, magnet 90 of electric lock L, to (-).

With the parts in this normal condition, if there is no train on the detector track circuit and the track relay T is energized, the electric lever lock L may be energized, so 95 that the lever LV may be moved to the reverse position; and since the relay LR is also energized, power may be applied to the switch machine to operate it to the reverse position, and cause it to generate dynamic 100 indication current, all in the way characteristic of this type of system, which need not be explained in detail. If, however, the detector track circuit is occupied, the electric lever lock L can not be energized, and the 105 relay LR is also de-energized, so that power can not be applied to the switch machine. In order that the operator may know when normal operation is possible, a lever lamp 50 is preferably employed, energized over a circuit from (+), through the front contact 23 of the track relay T, wires 33, 37 and 38, contact 19 of emergency release device ER, wires 39, 40, and 51, front contact 52 of relay LR, wire 53, lamp 50, to (-). 110

If, for any reason, after the lever LV has been operated, while the detector track circuit was unoccupied, a train should enter this detector track circuit while the switch machine is operating, the dropping of the track 120 relay T and the power control relay LR at once cuts off the supply of power to the switch machine and stops its operation. Under certain conditions, the switch machine might be thus stopped in mid-stroke; but this condition is considered to be preferable, particularly for subways; but if desired, arrangements may be made, such as disclosed in the Howe Patent, No. 1,550,611, above mentioned, so that the switch machine will 125 130

complete a cycle of operation once started before the detector track circuit becomes occupied.

Assume now that it becomes necessary, for some reason, to operate the switch machine by hand, either because it is out of order or adjustment, or some of its control devices are not operating properly, or there is some obstruction in the points which has to be removed, or the like. Before the hand crank can be inserted, the guard plate 25 must be shifted to open contacts 28 and 29, and this breaks the stick circuit for the relay P, which in turn, being de-energized, opens its front contact 11 and de-energizes the relay LR, thereby cutting off the supply of power to the switch machine. The protective relay P, once de-energized in this way, remains de-energized, even after the hand cranking is completed and the guard plate 25 is restored to the normal position to close the contacts 28 and 29; and before power can again be applied to the switch machine, the reset button RS must be operated to close the pick-up circuit for the relay P, which may be traced from (+), through the contact 12 of the reset button RS and its normally open contacts 42, wires 43 and 32, relay P to (-).

Thus, after the switch machine has been cranked by hand, and the guard plate 25 has been restored, the reset button RS must be specially manipulated before power is restored to the switch machine. This reset button is preferably located in the tower, and may be actuated by the operator upon instruction from the maintainer at the switch, if so desired; or, the key to obtain access to the reset button RS may be held only by the maintainer, so that he is required to return to the tower and operate this reset button after having cranked the switch machine by hand. Also, if so desired, the reset button RS may be located in a suitably sealed or locked box adjacent to the switch. The object of the invention is to require special manipulation to restore power to a switch machine that has been hand operated, and the reset button RS may be located or safeguarded in any suitable way to accomplish this purpose.

When the reset button RS is operated to energize the relay P, the normally closed contacts 12-35 of this reset button are opened, so that the relay LR remains de-energized, even though the relay P is restored. Consequently, the reset button RS must be returned to the normal position to permit energization of the relay LR and the application of power to the switch machine. This prevent leaving the reset button RS accidentally or intentionally in its actuated or resetting position.

Under certain conditions, particularly in the case of a track circuit failure, it may become necessary to operate the switch by

power in the regular way, even though the track relay T, or other approach or locking relays governing the energization of the lever lock L and the lock control relay LR, are de-energized, and act to prevent the normal power operation of the switch. For this purpose, the emergency release device ER is provided.

To understand the functions and operation of this emergency release device ER, assume that the detector track circuit has failed for some reason, and that the front contact 23 of the track relay T is open. This de-energizes the relay LR, and prevents the energization of the lever lock L. Under these conditions, after taking suitable precautions to be sure that it is safe to operate the switch, the operator by turning the crank 15 may move the spindle 14 to the left from the normal position shown to the first operated position, indicated by the dotted line 1, thereby closing a circuit for energizing the electric lock L which may be traced from (+), wires 44 and 45, contact 18, wires 46 and 40, latch contact 5, wire 41, electric lock L to (-). This permits the operator to move the lever LV to the other indication position, establishing at the lever contacts the next operating circuit for the switch machine, but since the relay LR is still de-energized under the conditions assumed, no operation of the switch machine occurs. The operator, after moving the lever LV, must bring the spindle 14 into the second operated position by turning the crank 15 further, indicated by the dotted line 2, thereby establishing a circuit for energizing the relay LR, which may be traced as follows:—from (+), wires 44 and 47, contact 18, wires 48 and 37, front contact 11 of the relay P, (which is assumed to be energized), and thence through the relay LR the same as in the normal energizing circuit for that relay. This permits the application of power to the switch machine; but before the signal 21, governing traffic over the switch can be cleared, the emergency release device must be cranked back to its initial or normal position shown to close a circuit through its contact 20, the complete control circuits for the signal not been shown, since they will take the usual form well known in the art.

It should be noted that the lever lock L and the power control relay LR are energized in different positions of the emergency release device ER. Consequently, for safe operation of the switch, while the detector track relay T, or equivalent route or approach locking relays (not shown), are de-energized, the operator must manipulate the emergency release device, first to a position to release the lever, and then move the lever, and then operate the emergency release device again to a position to energize the relay LR and apply power to the switch machine. Thus, the emergency release device ER can not be carelessly

ly or accidentally left in a position where the switch machine can be operated by power independent of the normal safeguards for such power operation; but for each such emergency operation of the switch machine, the operator must make a special manipulation, so that he is required to take suitable precautions, in accordance with the rules, for each power manipulation of the switch under such emergency conditions.

The particular construction and arrangement of parts and circuits shown and described is merely typical or representative of one specific embodiment of the invention; and it should be understood that the invention is applicable to various types of power interlocking, and is susceptible of considerable modification and adaptation to fit different conditions encountered in practice.

What I claim is:—

1. In a power interlocking system, a switch machine, means permitting hand operation of the switch machine and including a manually movable member which must be shifted before this machine can be operated by hand, electrically operable power control means for cutting off the supply of power to said switch machine controlled electrically and rendered effective by the movement of said member, said power control means when once operated remaining in that condition until specially restored, and manually operable means for restoring said power control means.

2. In a power interlocking system, a switch machine, means when in a changed condition permitting manual operation of said switch machine, means including a normally energized stick relay governed by said first mentioned means for controlling the application of power to the switch machine, and a manually controlled pick-up circuit for said stick relay.

3. In a power locking system, a switch machine having contacts opened to permit hand operation thereof, a normally energized stick relay acting when de-energized to interrupt the supply of power to said switch machine, a stick circuit for said relay including said contacts, a manually operable reset circuit controller, and a pick-up circuit for said relay including said circuit controller.

4. In a power interlocking system, a switch machine having contacts opened when it is operated by hand, a detector track circuit, a stick relay having its stick circuit broken by the opening of said contact, a power control device for cutting off the supply of power to said switch machine, said device being actuated by said stick relay when de-energized and by said detector track circuit when occupied, and a manually operable circuit controller movable to establish a pick-up circuit for said stick relay, said circuit controller when in its moved position rendering said

power control device effective to cut off the supply of power to the switch machine.

5. In a power interlocking system, a switch machine and a control lever therefor, a detector track circuit, a lock for said lever controlled by said track circuit, a power control device for governing the supply of power to said lever also controlled by said track circuit, and an emergency release device effective in one position to render said lever lock ineffective independently of its control by said track circuit, and in another position to govern said power control device to supply power to the switch machine independent of the control of said track circuit.

6. In a power interlocking system, a switch machine, a control lever, a lever lock, a power control device, a detector track circuit governing both said lock and said power control device, and an emergency release device effective in different positions to actuate said lock and power control device independently of their control by said track circuit.

7. In a power interlocking system, a control lever, a lever lock, a power control relay, a detector track circuit controlling both said lever lock and said power control relay, circuits for energizing said lock and said power control relay independently of their control by said detector track circuit, and a manually operable release device effective in different positions to close said circuits.

8. In an interlocking system, a control lever, an electric lever lock, a power cut-off device, means for rendering said lever lock and power cut-off device effective, and other manually operable means for rendering said lock and power cut-off device ineffective separately and independently and in different conditions of said means.

9. In a safety system for power-operated switches, a switch machine, a control lever in a tower at a point distant from said switch machine for governing the operation thereof, means permitting hand operation of the switch machine and including a manually movable member which must be shifted to an abnormal position before the switch can be operated by hand, an electrically operable power control device in the tower controlling the supply of current to said control lever, said device being actuated by the movement of said member to its abnormal position to cut off the supply of power to said switch machine, said device when changed to its abnormal condition remaining in that condition until specially restored, and manually operable restoring means in the tower for restoring said power control device to normal, said restoring means when in its restoring position acting independently of said device to prevent the application of power to the switch machine.

10. In a safety system for power-operated switches, the combination with a power-oper-

ated switch machine, a control lever, a detector track circuit adjacent the switch, said switch machine having an opening adapted to receive a hand crank for operating the switch machine by hand, a manually movable member adapted to obstruct said opening and which must be shifted before said hand crank can be inserted in said opening, and an electrically operable power control device controlled jointly by said detector track circuit and by said manually movable member for cutting off the supply of current to the contacts of said control lever if said track circuit is occupied or said manually movable member is in its shifted position.

11. A system for protecting power-operated switch machines comprising, a switch machine having a crank socket for permitting hand operation, a movable guard plate normally obstructing said socket, contacts opened by movement of said guard plate to give access to the crank socket, a normally energized stick relay acting when de-energized to prevent operation of said switch machine, a stick circuit for said relay including said contacts, a manually operable reset circuit controller movable to a restoring position to establish a pick-up circuit for said stick relay, and means associated with said circuit controller for independently preventing operation of the switch machine while said circuit controller is in its restoring position.

12. In a system for protecting the operation of power switch machines, a control lever, an electrically operable lever lock for preventing movement of said lever to its controlling positions, a power control device governing the supply of current to the contacts of said control lever, a detector track circuit, normal energizing circuits for said lever lock and said power control device both simultaneously controlled by said detector track circuit, release circuits for energizing said lever lock and said power control device independently of said detector track circuit, and an emergency screw release effective in different positions to close said release circuits separately.

13. In a system of the type described, a switch machine provided with means for permitting its hand operation and having crank contacts which must be opened before said switch machine can be operated by hand, a control lever for governing the operation of said switch machine, a detector track relay, a normally energized stick relay having a stick circuit including said crank contacts, a power control relay governing the supply of current to the contacts of the control lever, an energizing circuit for said power control relay including a front contact of said stick relay and a front contact of said detector track relay, and a manually operable reset circuit controller having normally closed contacts and normally open contacts, said normally

closed contacts of said circuit controller being included in said energizing circuit for the power control relay, said normally open contacts of said circuit controller being included in a pick-up circuit for said stick relay.

14. In a system of the type described, the combination with a power-operated switch machine and a control lever therefor, of an electric lock for said lever, a power control relay governing the supply of current to the contacts of said lever, an emergency screw release device having normally closed contacts and two normally open contacts, said contacts all being closed in different positions of said release device, an energizing circuit for said electric lock including said normally closed contacts, and other energizing circuits for said electric lock and said power control relay respectively including the normally open contacts of said screw release device.

In testimony whereof I affix my signature.
FRANK BENEDICT.
